WALL STRUCTURE AND METHOD OF
PRODUCING SAME

Harvey B. Lindsay, Evanston, Ill.

Application April 3, 1940, Serial No. 327,712

12 Claims. (Cl. 189—34)

My invention relates more particularly to structures involving, generally stated, framing members and relatively lightweight metal sheets as distinguished from interstitial metal material such as screening, or other mesh material, or expanded metal, extending across openings in the framings, and more especially, though not exclusively, to structures involving framing members which when joined together at ends and/or intersections form a skeleton framework with the sheets extending across the openings therein, as for example in the case of metal huts, one-story industrial buildings, railroad cars, partitions, deck covers and hatches, truck bodies, cooler rooms, shipping containers, and structures for many other uses, whether insulated or not, particularly where a high strength-weight ratio may be desired.

The invention also relates to the tensioning of the sheets on the framings, more particularly of the order of at least 100 pounds per lineal foot of sheet edge, my present application being a continuation in part of my application for United States Letters Patent Serial No. 214,785, filed June 20, 1938, which latter is a continuation in part of my application for United States Letters Patent Serial No. 187,056, filed January 26, 1938.

As a preface to the statement of my objects in devising the invention, it may be stated that sheet metal, as for example, sheet steel of the lighter gauges, such as 22 gauge and thinner, is ordinarily rolled by the so-called "pack-rolling" method, and then annealed, such rolling resulting generally in the thickness, and to some degree also the temper, of such a sheet varying considerably over its area, the sheet, as for example of 26 gauge, often being .003" thicker in some portions than others.

Such variations in thickness (as much as 20% and sometimes more) not to mention variations in temper, cause the sheet to present what are called "hard" and "soft" spots, rendering the sheet very far from uniform in the relation between pulling effort and elastic stretch of the sheet, viz., the actual temporary elongation of the metal below its yield point (elastic limit) when subjected to a given pulling force insufficient to reach the yield point. In other words, assuming the rigid gripping of the sheet edges by means operating to tension the sheet, stretching it within its elastic limit, the tension stresses are then concentrated at certain points or portions of the edges of the sheet though the grip and pulling movement is perfectly uniform along all edges, this usually causing waves or ripples

5 in the sheet, and thus such a sheet, in use, is subject to yielding at such points of concentrated stress long before the sheet as a whole will yield were the total pull or stress spread evenly over the entire edge of the sheet and consequently over the entire sheet. Such irregularities in sheet metal have therefore presented a condition which must be met in the production of flat wall structures in which the sheets are to be assembled in tensioned condition, with framings, with the sheets in the desired flat uniformly tensioned condition, thus avoiding stress concentrations and/or waves in the sheet.

10 Furthermore, the fact that sheets, as for example hot-rolled annealed steel sheets, will stretch only slightly before exceeding their elastic limit, a 36" wide such sheet stretching only about $\frac{3}{64}$ " across its width before exceeding its elastic limit, presents an additional condition to be met in the producing of a structure such as above referred to.

15 Certain of my objects are to provide lightweight metal structures, such as housing or partition structures, and comprising framings and panel sections of sheet metal in which an exceptional and unique strength-weight ratio is secured.

20 To provide in a structure such as above referred to, and particularly where the framings are joined together as stated to form a skeleton framework, for the holding of the framings, and when connected together, the skeleton framework, rigid to the degree desired without the necessity of braces, gussets, diagonals, and similar structure added to the framings or framework, as has heretofore been necessary in lightweight structures such as for example in the case of the specific structures above enumerated.

25 To provide adequate resistance against the severest wracking and other stresses in the plane of the wall by means of the sheet metal itself, instead of by the usual braces, gussets, diagonals, etc., in the framings.

30 To provide a unique strength in a panel or assembly of panels against transverse pressure or stress, without permanent distortion thereof, by the use of light weight sheet metal instead of by the customary heavy construction.

35 To provide for so tensioning the sheets that they become leveled, in which condition they are maintained in the completed structures, thus eliminating the wavy condition presented by the lightweight sheets, not so tensioned, in their assembled relationship to framings.

40 50 To provide for the placing of the sheets, in the

erecting of the sheets and the framings, under a perfectly uniform tension in all directions and holding them in this condition, such tension being within the elastic stretching limits of the sheets and the elastic bending and compression limits of the framings.

To provide for the overcoming of irregularities of resistance to elastic stretch inherent in commercial sheets such, for example, as ordinary hot rolled annealed steel sheets of the lighter gauges as, for instance, 22 to 30 gauge or even thinner, as above pointed out, and in doing so meet the condition, for example, in the case of steel sheets, of the very slight elongation of the sheets before exceeding the elastic limit.

To provide for governing the degree of such uniform tension in the sheets in order to meet varying needs of various uses.

To provide method or means whereby the above-mentioned objects may be attained; and other objects as will be manifest from the following description.

Referring to the accompanying drawings:

Figure 1 is a view in side elevation of a portion of a car body embodying my novel construction with the sheets tensioned in accordance with my novel method.

Figure 2 is a fragmentary enlarged sectional view taken at the line 2 on Fig. 1 and viewed in the direction of the arrow.

Figure 3 is an enlarged sectional view taken at the line 3 on Fig. 2 and viewed in the direction of the arrow showing the sheet-securing bar, forming a part of the wall portion, in spaced relation to the structure with which it cooperates.

Figure 4 is a fragmentary sectional view like Fig. 3 and of the structure therein shown, showing the sheet-securing bar in position preparatory to initiating the operation of tensioning the sheet.

Figure 5 is a fragmentary sectional view like Fig. 3 showing a position occupied by the sheet-securing bar in the operation of tensioning the sheet.

Figure 6 is a fragmentary sectional view like Fig. 3 showing a modification of the structure, the sheet-securing bar being shown in spaced relation to the structure with which it cooperates.

Figures 7, 8 and 9 are fragmentary sectional views like Fig. 6 of the structure therein shown, Fig. 7 showing the sheet-securing bar positioned preparatory to initiating the operation of tensioning the sheet, Fig. 8 showing this bar in one position occupied by it in the tensioning of the sheet; and Figure 9 showing the bar in its final seated sheet-tensioned position; and

Figures 10, 11 and 12, fragmentary sectional views like Fig. 3 illustrating several other modifications of the invention.

In the particular construction shown the car body of which the wall structure illustrated is a part, is supported on an underframe comprising cross bearers 13 carried by car trucks (not shown) and a surrounding frame formed of channel side sills, one of which is represented at 14, and end sills.

Extending over and along the end and side sills are angle irons one of which is shown at 15, with a metal sheet, hereinafter referred to, interposed therebetween, the angle irons and sills being secured together in any suitable way, as for example by bolts or rivets.

Superposing, and secured to, the underframe is a skeleton car-body-forming framewise struc-

ture comprising portions of the side walls, end walls and roof of the car.

This frame-like structure comprising both vertical and horizontal members, a portion of which for one side only of the car body is shown (which is sufficient for illustrating my present invention) is formed of metal bars 16 of channel shape with their channels 17 facing outwardly, these bars preferably having oppositely extending flanges 18 on their free edges; openings thus being presented between the bars 16 for receiving metal sheets spanning them to be held in position on the framework by means as herein-after described.

The various openings provided by the framework are closed with metal sheets 19 of any suitable kind, such as for example sheet steel, the marginal edges of which, flanged as herein-after described before applying them to the framework, extend into the channels of the several frame bars 16 in which they are engaged by the bars 20, preferably of channel form as shown, which in being moved inwardly in the channels 17, exert force against the marginal edges of the sheets in a direction to tension the sheets and preferably exert force against these marginal edges for clamping them against the bottoms 17a of the channels 17 to positively maintain the sheets in tensioned condition, the bottom surfaces 17a as shown being substantially normal to the inner surfaces of the adjacent side walls of the channels 17.

The bars 20, forming tensioning members, are forced into the channels 17 and held in seated position therein by any suitable means, as for example screws, rivets or bolts 21, rendering these bars and consequently the respective sheets individually removable for replacement or substitution in the event they become damaged, or it be otherwise desired to remove them.

To counteract the tension of the sheets on the longer frame members, "spreader-bars," one of which is shown at 16a, are inserted as compression members and firmly fastened to the channel bars 16. These spreader bars also serve to prevent any tendency of the channels to bend open.

In the particular construction shown the metal sheet above referred to as interposed between the angle irons 15 and the sills and which is represented at 22, forms a floor for the car body with its edges upwardly bent as represented at 23 and the terminal portions of its edges flanged as in the case of the sheets 19, these flanged portions extending into the lower horizontal ones of the channels 17 and being tensioned and held in place by the lower ones of the bars 20.

Referring to the construction shown in Figs. 1 to 5, inclusive, which may be typical of all of the marginal edges of the several sheets and represents one form in which the flanges on the sheets may be provided, this construction involves the bending or drawing of the edge of the sheet to form a flange 24 the terminal edge of which is bent back to form a relatively wide hook 25 of substantially arcuate shape in cross section, shown as substantially semi-circular, to receive the adjacent leg of the bar 20, the hook thus being engaged by the bar 20 and becoming deformed thereby upon the moving of this bar inwardly in the channel 17, the edge of the sheet becoming clamped firmly in deformed condition against the bottom 17a of the channel in the final movement of the bar 20 to seated position.

As shown in Figs. 3 and 4, the hook 25 is of

such depth that when the sheet is initially applied to position on the framework, the bottom surface 26 of the hook is spaced from the bottom 17a of the channel 17.

In the movement of the bar 20 inwardly in the channel 17 from the position shown in Fig. 4 toward the position in which it clamps the deformed hook portion against the bottom of the channel as shown of the bar 20 in Fig. 2, it causes the hook to become unrolled toward straight condition into engagement at its outer margin with the bottom of the channel as shown in Fig. 5, in which movement of the hook its marginal portion must be free of obstruction, the sheet in this operation becoming somewhat irregularly tensioned, due to the resistance of the hook to deformation, and the irregular resistance of the sheet to elastic stretch as described.

As the bar 20 continues its inward movement from the position shown in Fig. 5 toward the position shown in Fig. 2, it exerts continuing deforming action on the hook 25 in a direction toward the bottom 17a of the channel to force or deform the hook into the interior angle between the bottom of the channel and the adjacent side wall of the latter and in this movement increases the tension in the sheet. The force required to do this is less if the sheet will stretch sufficiently so that the margin of the sheet will travel with the toe of the bar and the latter can merely bend the sheet continuously sharper on one line of contact between the toe and the sheet, but greater force is required in this action, if the sheet will not so stretch and the toe of the bar 20 (on its inward travel) must therefore successively so bend or draw new lines of contact into sharpening angles and necessarily at the same time substantially straighten out the previous lines of bend. This movement of the tensioner bar toe from one line of contact with the hook portion to another lower down thereon (all under severe drawing stress on the sheet hook material) I call "slippage" of the tensioner bar toe. Hence, as resistance to elastic stretching (tensioning) of the sheet is less opposite the "soft" portions thereof than opposite the "hard" portions, the inwardly moving bar toe will continue to draw down the sheet margin (increase the sheet tension) opposite the "soft" portions while having to bend new lines of sharp angularity opposite the "hard" portions, or in other words, causing "slippage" of the tensioner bar toe opposite the "hard" portions of the sheet while not opposite the "soft" portions. This action continues until the tension of the "soft" portions of the sheet have been thus brought up to that opposite the "hard" portions, when further inward travel of the bar to its final position in which the sheet is clamped by the bar 20 against the bottom 17a of the channel 17 (Fig. 2), simply increases the thus equalized tension of the whole sheet, because of the progressive deformation of the hook along its entire length previously described, until or unless the thus equalized tension in the sheet becomes the equivalent to the bending force required to further deform the hook portion into the angle between the channel bottom and side, whereupon the aforesaid "slippage" occurs all along the hook portion, until or unless further irregularities of tension develop in the sheet, when this equalizing action again takes place; and so on to final clamping.

It is to be understood that I have explained this action as though it were distinctly intermittent, in order to make it clear. Actually it is

probably more nearly continuous, but in any event it results in a perfect and uniform tension throughout the sheet.

It is probable that with relatively stiff sheets (e. g. 22 gauge hot rolled annealed steel sheets) some relatively small part of this equalization takes place before the round hook edge is uncircled sufficiently to contact the bottom of the channel, but this does not seem to be the case with lighter gauges of such sheets.

From the foregoing it will be understood that in operating the tensioning bars at each edge of the sheet, the sheet is placed under substantially uniform tension in both directions throughout its area, the tension produced causing measurable stretching of the metal within its elastic limit.

As it is undesirable to have too wide a channel in the framing channel members (of the preferred light shape shown) which would seriously increase the bending movement and consequent tendency of the channel to "spread," it is desirable to have the hook of the sheet flange, which obviously must be unobstructed in uncircling or opening out, as narrow or of as short a radius as is consistent in providing the action above described. This being the case, and realizing that the greater part of the tensioning effect is obtained after the margin of the sheet contacts the bottom of the channel, particularly in the case of the lighter sheets (e. g. 26 or 30 gauge hot rolled annealed steel sheets), and as the ordinary such sheets require some pulling down by the tensioner bar before they become flat though not in any appreciable tension, and as in such lighter gauges, even to do this may partly uncurl the round hook, it is desirable in such cases to form a hook which will not so uncurl without compensating tensioning effect on the sheet. For this purpose I prefer a hook shaped as shown in Fig. 6, having a sharp bend with a very small radius, say inside radius of the order of .020", and a bar toe of approximate conformation, so that its outer 45 slightly rounded edge is the only line or lines of contact with the sheet hook, thus preventing its inner edge from spreading the hook by striking the wider curved portion of the hook adjacent its edge.

Referring to the construction shown in Figs. 6 to 9, inclusive, particularly useful in developing relatively high tension values in the sheet within the elastic limit of the metal of the sheet, such as are desirable in railroad cars, trailer bodies, marine structures, etc., the hooks represented at 27 are made of general acute angular form with the juncture of the flange portions 28 and 29 thereof at the bend 30 of each hook (the flange portion 28 being substantially flat and the flange portion 29 of general arcuate shape), describing a relatively short radius and the terminal edges of the legs of the tensioning bar herein represented at 31 and corresponding to the bar 20, beveled as represented at 32, with their toes 33, at which the bar engages the interior corners of the bends 30 closely adjacent the side walls of the channel along which the bar extends, preferably slightly rounded to conform to the shape of said interior corners as shown at 34.

It will be immediately seen that with the arrangement shown in Fig. 6 the bending leverage of the tensioner bar toe is so short that very considerable pressure can be exerted by the bar in its inward movement, toward the position in which it clamps the deformed hook against the

bottom $11a$ of the channel, Fig. 10, before the hook opens out, during which movement in which the hook remains undeformed several hundred pounds tension per foot of edge may be developed in the sheet, and the remaining small distance the bar travels (after the marginal part of the hook has contacted the bottom of the channel) should be sufficient to equalize and develop the high tension in the sheet obtainable by using this form of hook.

While I have been able to find no formulae whatever governing the forces required for the progressive angular deforming of a given metal sheet as described, I have consistently found it true in all my tests that that force is always less than the force required to reach the yield point (elastic limit) of that sheet. Hence whatever form of hook is used (short of so sharp a bend as to injure the metal) there is apparently no danger of exceeding the yield point of the metal sheets in my invention. This being the case, it is apparent that when the tension in the sheet has been equalized and the force required to further increase the sheet tension is greater than the force required to further progressively deform the flange hook into the corner of the channel, then the sheet edge will not travel with the tensioner bar, but the latter will progressively deform the hook until the final seating and clamping position of the bar is reached, the highest tension reached being maintained.

In order substantially to control this tension, three factors toward such control are available.

(1) The shape of the hook; the greater the resistance to unbending or unrolling, the greater the contribution to tension of the sheet.

(2) The relative stiffness of the metal sheet; the stiffer the material of the hook, the greater the resistance (of any given form of hook) to unbending and particularly to successive deforming of the hook material into the corner of the channel, and consequently the greater the contribution to increasing the tension of the sheet.

(3) The distance (when the sheet is in place on the channel) from the bottom of the hook to the inside bottom of the channel; provided this distance is not too great to permit the hook margin in unbending to contact the bottom of the channel as described, then generally speaking, the less this distance the less the contribution of this factor to the tensioning of the sheet.

By using these factors either singly or in any degree of combination, not only is a wide range of tensioning control provided, but in addition such control can be largely made to conform to the requirement of the particular structure being manufactured—such as lightness, cost, etc.

I prefer to use the hook with the reasonably sharp bend with its co-ordinating tensioner bar toe, as shown in Fig. 6, as with this arrangement it is possible to produce higher sheet tensions, as stated. Then, where such high tensions are not needed, but it is more important to avoid fatigue of the metal by lower maintained stresses, I reduce the distance from the bottom of the hook to the inside bottom of the channel.

As examples of preferred practice, producing uniform tension in the sheet, and involving the provision of the hook flanges on opposite edges of the sheet each flanged edge having one of the tensioning bars cooperating therewith, I quote the following (all using hot rolled annealed steel sheets and the distances specified between the hooks and the bottoms of the channels being between these parts in the initial posi-

tioning of the hooks in the channels with the bodies of the sheets in proper contact with the channel bars (16):

5

26 gauge. Tension desired about 100 lbs. per foot of edge. Round hook (Fig. 3) with inside radius approximately $\frac{1}{16}$ ". Tensioner bar leg preferably not more than about $\frac{1}{4}$ " thick. Distance between bottom of hook and inside bottom $11a$ of channel approximately $\frac{1}{16}$ ".

10

Example No. 1

15

26 gauge. Desired sheet tension about 300 lbs. per foot of edge. Round hook (Fig. 3) with inside radius approximately $\frac{1}{16}$ ". Tensioner bar leg preferably not more than about $\frac{1}{4}$ " thick. Distance from bottom of hook to inside bottom $11a$ of channel approximately $\frac{3}{32}$ ".

20

Example No. 2

25

26 gauge. Desired tension about 500 lbs. per foot of edge. Round hook (Fig. 3) with inside radius approximately $\frac{1}{16}$ ". Tensioner bar leg preferably not more than about $\frac{1}{4}$ " thick. Distance from bottom of hook to inside bottom $11a$ of channel approximately $\frac{3}{32}$ "; or hook as in Fig. 6 with its inner radii approximately .020", and the bottom surface 35 of its bend approximately $\frac{3}{32}$ " from the bottom $11a$ of the channel.

30

Example No. 3

35

24 gauge. Desired tension about 1000 lbs. per foot of edge. Hook as in Fig. 6 with inside radius of approximately .020" but the distance from bottom surface 35 of hook to inside bottom $11a$ of channel approximately $\frac{1}{8}$ ".

40

It is obvious that, if the sheet is fixedly anchored at one edge and tensioned from the opposite edge only, it is desirable to double the distance between bottom of hook and channel bottom that is required where the tensioning action is coincidentally operated at both edges.

45

In this general connection it is well to point out that in tensioning a sheet at both of opposite edges or at all edges, the operation should be of the continuous type, viz., partially and successively tightening the various tensioner bar involved, until all have been firmly driven home, similar e. g. to the usual practice in tightening the holding bolts of an automobile cylinder head block.

50

It is to be noted that if a sheet particularly "hard" or particularly "soft" throughout or having excessive "buckles" be encountered in duplicating the above examples, a corresponding variation in results must be expected. The above examples represent practice with sheets selected for reasonable flatness from average runs, and with the flanges die-drawn.

55

The modifications shown in Figs. 10 to 12 represent additional forms of structure in accordance with my invention, by which the results produced by the structures of Figs. 1 to 9, inclusive, may, at least to a material and useful degree, be attained, in the use of any of the structures of Figs. 10 to 12, inclusive, where relatively low tension in the sheet is desired, and as to Figs. 11 and 12 where the metal of the sheet is relatively brittle under bending first one way and then the other. In these cases, while some degree of control and tension possibly may be lost, it will be seen that the actions and their results, caused by the forcing home of the tensioner bar, will be substantially the same, in Fig. 10 after the sheet flange edge has contacted

70

75

the channel bottom 17a, and in Figs. 11 and 12 after contact of the tensioner bar toe with the sheet flanges, as in the cases above fully described (Figs. 3 and 6) after the hook has contacted the bottom of the channel.

The construction shown in Fig. 10 involves the bending of the edge portion of the sheet to form a flange 36 terminating in an outwardly bent flange or ledge portion 37 preferably of such width that when engaged and bent by the adjacent leg of the tensioning bar herein represented at 38 and corresponding to the bar 20, it will engage at its terminal edge with the bottom 17a of the channel 17 and will become clamped at this portion against the bottom 17a of the channel in the final seating movement of the bar.

In this construction it will be noted that the bar 38 once its downward pressure has overcome the resistance of the bent edges (of the sheet) to unbending, exerts force against successive portions of the ledge portion 37 in a direction toward the bottom of the channel 17 as the bar moves inwardly in the channel, thus exerting a pull on the sheet placing it in some tension, which pull is much increased after the terminal edge of the ledge portion contacts the bottom of the channel, the bar, in its final movement, clamping the tensioned sheet against the bottom of the channel.

The construction shown in Fig. 11 differs from that shown in Fig. 10 only in the respect that the flange of the sheet and represented at 39 and corresponding with the flange 36, is spaced from the adjacent side wall of the channel 17 in the initial assembling of the sheet with the bar 16, and its terminal flange portion represented at 40 and corresponding with the portion 37 of Fig. 10 extends at an obtuse angle to the flange 39 and initially engages at its edge portion with the bottom 17a of the channel. The bar 38 in moving inwardly in the channel thus acts against successive portions of the flanged portion of the sheet to exert a pull thereon because of successive deforming of the flange of the sheet, placing the sheet in tension and finally clamping the edge of the sheet in tensioned condition, against the bottom 17a of the channel 17.

In the construction shown in Fig. 12, the edge of the sheet is provided with a flange 41, without any reverse bend, the flange 41 inclining toward the medial line of the channel 17 and thus spaced from the adjacent side wall of the channel and being of such width that it engages the bottom 17a of the channel in the initial assembly of the sheet with the bar 16. Thus as the bar 38 moves inwardly it engages successive portions of the flange 41 progressively deforming it and placing the sheet in tension and finally clamping the edge of the sheet in tensioned condition against the bottom 17a of the channel 17.

If desired, the flange 36 of Fig. 10 instead of engaging the adjacent side wall of the channel in the initial assembling of the sheet with the channel bar 16, may be bent to extend in spaced relation thereto, as for example as shown of the flange 39 of Fig. 11. Furthermore, the flanges 24 and 39 of Figs. 3 and 11, may be bent to extend in contact with the adjacent side walls of the channels instead of being spaced therefrom as shown.

It should be apparent from this description and the drawings of various types of hook-portions that can be used, that, generally speaking, the more resistance to deforming the hook por-

tion offers, the greater the tension developed in the sheet. It should be equally evident that the hook must open out and deform, as described, in order to provide the possibility for the equalizing tension as described.

In all of the modifications shown in Figs. 10 to 12, inclusive, as in the case of the structures shown in Figs. 1-9, inclusive, non-uniformity of resistance of the sheet to pulling stress, exerted by the tensioning bar, due to "hard" and "soft" spots in the sheet, is compensated for and final uniform tension throughout the sheet is effected, by slippage, of the tensioning bar as described, during the inward movement of this bar to its final position, past those portions of the sheet-flange which are opposite the "hard" spots of the sheet as well as slippage of the tensioning bar along the entire length of the flange when the equalized tension in the sheet equals the force required for further inward movement of the tensioning bar, as described.

As above set forth one of the factors controlling the development of the final tension in the sheet in the case of Figs. 3 and 6, is the distance of the bend of the hook from the bottom 17a of the channel, the dotted lines in these figures representing different such initial spacings of the hooks. This also applies to Fig. 10—the closer the juncture between the flanges 36 and 37 is to the bottom of the channel the less the final tension in the sheet.

In Fig. 11 the closer the juncture between flanges 39 and 40 is to the bottom 17a of the channel and in Fig. 12 the less the angle of inclination of the flange 41 relative to the side wall of the channel 17, the less the final tension in the sheet.

If desired, in addition to the spreader bars 16a, the several bars 16 may be reinforced at suitable intervals to prevent spreading in the securing thereto of the metal sheets, as by providing clips 42 shown as of U-shape, applied to straddling position on the bars as represented of the clip in Figs. 2 and 3 where one such clip is shown as applied to one of the vertical channel bars 16, the clips being secured to the bars in any desirable way, as for example by welding them thereto.

The word "stretching" is used herein and in the claims in its popular sense and not in the sense of producing a permanent elongation of any dimension of the sheet or any portion thereof. In order to develop the full elastic strength of the sheets the tensile stress to which the sheets are subjected must not stretch the sheets beyond their elastic limit.

It is obvious that as to all of the structures shown the tensioning bars may be gradually forced home uniformly about the sheet or one side may be fully seated before initial stress is applied to the opposite tensioning bar, in which case the first applied bar will act only as an anchor.

Considering the action of the tensioning bar on any of the flanged edges of the sheet, to tension the sheet, such action is exerted on such edge in the anchored condition of the opposite edge of the sheet whether the tensioning bars at opposite edges of the sheet are operated simultaneously, or in repeated succession to gradually force home the tensioning bars about the sheet, or the edge opposite the edge being operated on by the tensioning bar is rigidly held, as for example by fully seating the tensioning bar at this edge before initial stress is applied to the

opposite tensioning bar or by providing any other desirable bar clamped in any way against, or rigidly connected with, the sheet as for instance by welding it thereto against yielding under the stress exerted by the tensioning means.

It will also be apparent that tension may be applied in one dimension only of the sheet, while securing many of the advantages of the invention.

The term "metallic sheet" as used herein and in the claims is to be understood to mean a commercial sheet such as is supplied to the trade, which sheets are always unequally resistant to a stretching force, being either thicker or harder or both in some portions than in other portions.

While I have illustrated and described certain particular embodiments of my invention and have disclosed certain procedures for the practicing of my improved method I do not wish to be understood as intending to limit the invention thereto as the embodiments shown may be variously modified and altered and the invention embodied in other forms of structure and the method practiced by other procedures, without departing from the spirit of the invention.

What I claim as new and desire to secure by Letters Patent, is:

1. The method of constructing a sheet metal panel which comprises: applying tensioning stress throughout the length of at least one margin of the sheet against anchoring resistance applied at the opposite margin; said stress sufficient to cause stretching of the metal of the sheet but within the elastic limit of the material; allowing slippage of the stress applying means relative to the sheet metal at any locations therealong opposite those portions of the sheet offering greater resistance to tensioning than other portions of the sheet; whereby to secure substantially uniform tension on all portions of the sheet; and anchoring the stress applying means to hold the sheet in tension.

2. A structure having an area to be spanned, with a channel member at one edge of said area, a sheet metal member spanning said area having a preformed flange at one of its margins terminating in a reversely bent hook portion at which said sheet extends into said channel in initially spaced relation to the bottom thereof, means at the opposite margin of the sheet metal member anchoring it in place, a tensioning member to enter said channel and be moved inwardly therein in engagement with said hook portion, said tensioning member in said movement bending said hook portion outwardly, said channel member being free of obstruction to outward bending of said hook portion by the tensioning member into engagement with the bottom of said channel, whereby said hook portion becomes deformed and tension is exerted on said sheet sufficient measurably to stretch the same, but within its elastic limit, and means for holding said tensioning member in sheet-tensioning position.

3. A structure having an area to be spanned, with a channel member at one edge of said area, a sheet metal member spanning said area having a preformed flange at one of its margins terminating in a reversely bent hook portion at which said sheet extends into said channel in initially spaced relation to the bottom thereof, means at the opposite margin of the sheet metal member anchoring it in place, a tensioning member to enter said channel and be moved inwardly therein in engagement with said hook portion, said channel member being free of obstruction

to outward bending of said hook portion by the tensioning member into engagement with the bottom of said channel, said tensioning member, in its initial sheet-tensioning movement bending

5 said hook portion into engagement, at its outer edge portion, with the bottom of said channel and thereafter deformingly forcing the hook portion toward the interior angle of said channel, whereby said hook portion becomes deformed 10 and tension is exerted on said sheet sufficient measurably to stretch the same, but within its elastic limit, and means for holding said tensioning member in sheet-tensioning position.

4. A structure having an area to be spanned, 15 with a channel member at one edge of said area, a sheet metal member spanning said area having a preformed flange at the one of its margins adjacent said channel member projecting into said channel, the free edge of said flange reversely 20 bent into hook form, the overall depth of said flange being less than the depth of said channel, means at the opposite margin of the sheet metal member anchoring it in place, a tensioning bar to enter said channel and enter and engage said 25 hooked portion substantially throughout the length of said hooked portion, and means to exert pressure on said bar, said tensioning member adapted to slip relative to said sheet at any locations therealong opposite to those portions of 30 the sheet which offer greater resistance to tensioning than other portions of the sheet in the operation of drawing said sheet, by said tensioning bar, to the desired tension.

5. In a structure of the class described, an 35 assembly of channel members bounding a polygonal area, a sheet metal covering for said area having preformed flanges at its margins projecting into the respective channels, the free edges of said flanges reversely bent into hook form, the 40 overall depth of said flanges being less than the depth of said channels, tensioning bars to enter said respective channels and enter and engage said hooked portions substantially throughout the length of said hooked portions, and means to exert 45 pressure on said bars, said tensioning member adapted to slip relative to said sheet at any locations therealong opposite to those portions of the sheet which offer greater resistance to tensioning than other portions of the sheet, in 50 the operation of drawing said sheet, by said tensioning bar, to the desired tension.

6. The structure of claim 4 in which the surface of said area joins the side of said channel in a curved surface.

55 7. The structure of claim 4, with the depth of the marginal flange predetermined to be clamped, by the tensioning bar, against the bottom of the channel when a predetermined tensile stress has been exerted on said sheet metal member, sufficient measurably to cause stretching of the metal within its elastic limit.

8. The structure of claim 5, with the depth of the marginal flanges predetermined to be clamped, by the tensioning bars, against the bottoms of the channels when a predetermined stress has been exerted on said sheet metal member, sufficient measurably to cause stretching of the metal within its elastic limit.

9. A structure having an area to be spanned, 70 with a channel member at one edge of said area, a sheet metal member spanning said area having a preformed flange at the one of its margins adjacent said channel member projecting into said channel, the free edge of said flange reversely 75 bent into hook form, the overall depth

of said flange being less than the depth of said channel, said hook portion being curved with its concave surface facing in the direction of the outer side of said channel and said flange being substantially flat, said hook extending at substantially an acute angle to said flange and connected with said flange at a sharp bend the interior angle of which is rounded, means at the opposite margin of the sheet metal member anchoring it in place, a tensioning bar to enter said channel and enter and engage said hooked portion substantially throughout the length of said hooked portion, and means to exert pressure on said bar, said tensioning member adapted to slip relative to said sheet at any locations therealong opposite to those portions of the sheet which offer greater resistance to tensioning than other portions of the sheet in the operation of drawing said sheet, by said tensioning bar, to the desired tension.

10. The method of constructing a structure embodying a sheet metal panel including development of the tensile strength of the sheet metal to resist deformation of the panel in the plane of

the sheet which method comprises placing the metal of the sheet under tension by stress applied to the sheet against anchoring resistance and of sufficient intensity to cause measurable stretching thereof within its elastic limit, causing the tension as finally developed to be substantially uniform throughout the sheet by allowing slippage of the tension applying means relative to the sheet as certain parts of the sheet offer more resistance to stretching than other portions thereof.

11. The process of claim 10 in which the tensioning stress is applied in more than one direction.

15 12. A structure of the class described comprising a rigid metallic frame; a continuous metallic sheet secured upon said frame by continuous clamping means, under uniform tension in all directions in the plane of the sheet; the metal of
20 said sheet measurably stretched within its elastic limit thereby developing the tensile strength of the sheet throughout its area in all directions.
